CLAIM

The ornamental design for a ceiling fan blade, as shown and described.

DESCRIPTION

FIG. 1 is a top perspective view of a ceiling fan blade according to my new invention, with a ceiling fan shown in broken lines.

FIG. 2 is a bottom front perspective view of the ceiling fan blade of FIG. 1;

FIG. 3 is a right side elevation view of the ceiling fan blade of FIG. 1;

FIG. 4 is a front elevation view of the ceiling fan blade of FIG. 1;

FIG. 5 is a left side elevation view of the ceiling fan blade of FIG. 1;

FIG. 6 is a top view of the ceiling fan blade of FIG. 1; and, FIG. 7 is a bottom view of the ceiling fan blade of FIG. 1. The broken lines shown in FIG. 1 illustrate environmental structure, and the broken lines in the remaining views illustrate portions of the ceiling fan blade. None of the broken lines form part of the claimed design.
